UNITED STATES PATENT OFFICE.

LOUIS L. LEMAY, OF PEPPERELL, MASSACHUSETTS.

HEADLIGHT-SUPPORT.

No. 882,898.

Specification of Letters Patent. Patented March 24, 1908.

Application filed November 29, 1907. Serial No. 404,227.

To all whom it may concern:

Be it known that I, LOUIS L. LEMAY, a citizen of the United States, residing in Pepperell, in the county of Middlesex and State of Massachusetts, have invented new and useful Improvements in Headlight-Supports, of which the following is a specification.

It has been found in practice that when an electric or other street-car is rounding a curve, the head-light, which is commonly supported by and in front of the dashboard, loses to a large extent its effectiveness because the rays of light, which while the car is running on a straight track illuminate the track centrally and between the rails, are when the car is on a curve thrown one side of the center of the track, or even to one side of the track itself, illuminating a region outside of the track instead of the rails and the space between them. This is, of course, because the advancing end of the car is when on a curve non-central with the track, the line of the center of the car being practically tangential with the line of the center of the track. My present invention has for its object to remedy this defect, and to so support and automatically adjust and direct the head-light that it will, even when the car is rounding a curve, face and illuminate the track and the portion between the rails as effectively as when the car is traveling over a straight track.

In carrying out this invention, I provide a pivotal support for the light which is sustained by the car-body or dashboard, and the light is turned on a horizontal plane by a mechanism intermediate thereof and the forward pivotal or radial truck common in modern cars as a curve is reached, and thus its rays are thrown on the track whether the car is on a straight or curved track, the direction of the rays being controlled not by the car-body whose front end projects toward the outside of the curve, but by the truck which is always radial with the track, and which being pivotally connected with the car-body is free to follow the curve, whereby the front end of the truck is necessarily more nearly radial with a curved track than the front end of the car-body.

The nature of the invention is fully described in detail below, and illustrated in the accompanying drawings, in which:—

Figure 1 is a side elevation of a portion of the front end of a street-car provided with my invention. Fig. 2 is a diagrammatic

view in plan of the forward truck of a car on a curved track, with my invention applied thereto, the general shape of a portion of the car-body being shown in dotted lines. Fig. 3 is an enlarged side elevation in detail, partly in section, showing the connection between the head-light and the front car-truck. Fig. 4 is an enlarged front elevation of the same. In Figs. 3 and 4 certain portions are represented as broken out.

Similar numerals of reference indicate corresponding parts.

Reference numeral 10 indicates a portion of an ordinary street-car-body, 11 being the dashboard, and 12 the forward truck pivotally connected at 13 in the ordinary manner with the car-body.

14 and 15 represent a pair of plates bolted to opposite sides of the dashboard, and there extends from the outer plate 14 a frame which comprises a pair of horizontal bars 16 suitably braced at 17, the outer ends of said bars 16 being rigid or integral with a vertical sleeve or tube 18. A vertical rod or shaft 19 extends through said tube and has bearings therein, said rod supporting a vertical yoke 20 in whose upper ends 21 there is hung an ordinary head-light 22.

The lower end of the vertical rod 19 has rigidly secured to it at 23 a block 24 which is horizontally bored to receive a horizontal tubular holder 25 which is recessed at 26 (Fig. 3) to receive the lower end of the rod 19. Said parts 24 and 25 rotate therefore with the rotation of the rod 19. This tubular holder 25 supports slidingly a horizontal rod 27 to whose front end is rigidly secured the head 28 of a vertical rod 29 which extends down through one of the holes 30 near the front end of a horizontal bar 31 which is rigidly secured at 32 (Fig. 1) near its rear end to the front portion 33 of the forward truck 12. The portion of the rod 29 which is in one of the holes 30 is surrounded by a block 34 vertically bored to receive said rod and screwed into the hole through which the rod extends, said block serving to prevent relative lateral movement of the rod 29, but allowing rotative movement thereof. The block can of course be removed from one hole to another as desired.

In practical operation, when the car is on a straight track the head-light is parallel with the front end of the car-body and with the front end of the forward truck, and the rod 27 is parallel with the bar 31, and is mid-

way between and parallel with the rails of the car-track. When the car enters upon a curved portion of the track, the head-light, which is connected with the car-body by the parts 14, 16, 18, is partially rotated, such rotation being directly produced by the vertical rod or shaft 19 which is rotated by the block 24 on the tubular holder or slide-way 25, said holder being rotated by the rod 27 which is swung horizontally by the engagement of its front end with the head of the vertical rod 29, said vertical rod being swung horizontally by the front end of the bar 31 which, being rigidly connected at its rear end with the pivoted truck is swung by the rotation of said truck with relation to the car-body as it enters and passes over the curve. During this movement of the parts the rod 27 is sliding horizontally in the holder 25. When the forward truck enters on a left hand curve it rotates toward the left on its pivot 13, as illustrated in Fig. 2, and thus swings the bar 31 toward the left, pulling the rod 29 in the same direction, sliding the rod 27 forward in the tubular holder 25, and rotating said holder, and of course the vertical rod 19 and the lantern 22 toward the left, thus causing the head-light to take a position which is approximately radial with the curved track and in which it throws the rays of light forward between and upon the rails while the car is passing around the curve, instead of one side of the rails beyond the outer side of the curved track, as would be the case if the head-light were non-rotatively connected with the car-body.

When the truck enters a curve in the opposite direction from that illustrated in Fig. 2, it rotates toward the right on its pivot 13 with relation to the car-body and thus swings the bar 31 toward the right, pulling the rod 29 in the same direction, sliding the rod 27 forward in the tubular holder 25, and rotating said holder, and of course the vertical rod 19 and the lantern 22 toward the right, thus causing the head-light to take a position which is approximately radial with the curved track and in which it throws the rays of light forward between and upon the rails while the car is passing around the right hand curve.

It is obvious that as there is no direct pivotal connection between the mechanism beneath the car-body which controls the rotation of the head-light and the floor of the car-body, suitable allowance is possible for both the sidewise and lengthwise rocking of the car. The mechanism is prevented from injury when the car rocks sidewise by the tubular connection consisting of the rod 27 and the tubular holder 25, while vertical or lengthwise rocking is permitted without injury to the parts by reason of the rod 29 which extends down through one of the holes 30, space being left between the head 28 and block 34 to allow for relative vertical move-

ment at that point. Moreover the employment of slotted connections at pivotal points is rendered unnecessary, the slots being apt to become quickly clogged with dirt, while in the tubular connection 27, 25, the rod 27 quickly clears itself as it slides longitudinally in the tubular holder 25 and swings rotatively on a horizontal plane.

When a car accidentally leaves the track the truck is apt to be rotated to an extreme degree, especially if a chain intended to limit the extent of movement breaks. This extreme turning of the truck is rendered possible without injury to the mechanism inasmuch as the rod 27 can be pulled entirely out from the tubular holder 25 without injuring any of the parts of the device.

It is evident that this device is applicable to all cars or vehicles having pivoted or radial trucks, and to either end of the car or vehicle which happens to be operating as the forward end.

Having thus fully described my invention, what I claim, and desire to secure by Letters Patent is:—

1. An automatically-adjusting head-light supporting mechanism for street-cars and other vehicles, comprising a substantially vertical rotative support for the head-light, a supporting frame adapted to extend substantially horizontally from the car or vehicle-body and provide bearings for the rotative support whereby the head-light may be sustained in front of the dashboard, a substantially horizontal tubular holder rigidly connected with the lower end of said rotative support and constituting a horizontal slide-way, a substantially horizontal rod supported and adapted to slide horizontally in said holder, a bar rigidly connected with the truck and extending forward horizontally therefrom under said holder and horizontal rod, and a vertical pivotal connection between the forward portion of said rod and bar, for the purpose set forth.

2. An automatically-adjusting head-light supporting mechanism for street-cars and other vehicles, comprising a substantially vertical rotative support for the head-light, a supporting frame adapted to extend substantially horizontally from the car or vehicle-body and provide bearings for the rotative support whereby the head-light may be sustained in front of the dashboard, a substantially horizontal tubular holder rigidly connected with the lower end of said rotative support and constituting a horizontal slide-way, a substantially horizontal rod supported and adapted to slide horizontally in said holder, a bar rigidly connected with the truck and extending forward horizontally therefrom under said holder and horizontal rod and provided with vertical holes in its forward end, a vertical pivot-pin extending from the front end of the sliding rod into one

of said holes, and a stop arranged on said pin under the horizontal bar at a distance to allow vertical play of the pin in the hole, for the purpose set forth.

5 3. An automatically-adjusting head-light supporting mechanism for street-cars and other vehicles, comprising a substantially vertical rotative support for the head-light, means secured to the car or vehicle for supporting said rotative support at the forward end thereof, a substantially horizontal tubular holder rigidly connected with the lower portion of the rotative support and constituting a horizontal slideway, a bar extending 10 forward from the truck under the car-body, a horizontal rod adapted to move longitudinally and rotatively in said slideway, and a

pivotal connection between said sliding rod and stationary bar, whereby the swinging of the bar as the truck travels over a curve im- 20 parts longitudinal or endwise movement to the sliding rod and causes it to swing in a horizontal plane for the purpose of rotating the head-light support, and the tubular holder is adapted to rock on the horizontal 25 rod.

In testimony whereof I have signed my name to this specification in the presence of two subscribing witnesses.
